UNITED STATES PATENT OFFICE.

WILSON B. WIGLE, OF LONG BEACH, CALIFORNIA.

CASING HEAD FOR OIL WELLS.

Application filed November 10, 1925. Serial No. 68,188.

This invention has relation to a casing head designed to be detachably secured to well casings of oil wells that are being pumped for effectually directing the flow of gas and oil flowing therefrom through several valve controlled pipe lines.

It is the primary object of this invention to provide a casing head that can be conveniently used in connection with pumping operations and which will effectively seal the well so that the flow of gas and oil therefrom can be separately controlled.

A further object is to provide a construction in which the packing cap, flow lines, rod stuffing box, and anchoring means are combined in a single unitary head, whereby to effect economy in manufacture and simplicity of operation.

A further object is to provide a head formed of a plurality of parts held in fluid tight relation to each other, that may be readily disconnected from each other to permit of a ready withdrawal of the oil well rods and tubing when desired.

A still further object is to provide for the easy renewal of the casing head packings when the same become worn, and to provide a single means for effectively applying and distributing pressure to the packing members.

Other objects and advantages will become apparent as the description proceeds, reference being had to the drawings attached hereto and which form a part of the specification, in which:

Fig. 1 is a side elevation of the casing head attached to a well casing.

Fig. 2 is a central vertical section through the casing head attached to the upper end of a well casing.

Fig. 3 is a top plan view.

The improved casing head preferably consists of a cylindrical body 5 threaded exteriorly on its lower end for attachment to the upper screw threaded end of the well casing 6. Body 5 is provided in its cylindrical wall with diametrically disposed gas flow pipes 7, 8, controlled by the usual valves (not shown), and adjacent its upper end is cut away to form an internal seat 9, for the reception of a split sleeve 10, the exterior flanges 11 of the sleeve engaging the seat 9. This sleeve is provided with a downwardly extending tapered bore 12, in which are disposed slips of usual form designed to engage and support the oil tube 13, when

it is desired to withdraw the same from the well. Sleeve 10 is of smaller exterior diameter than the internal diameter of the collar 5, in order that the gas flowing from the well may pass therebetween to the gas flow pipes.

In order to support the oil tubing 13 within the casing a cylindrical spider 14 is provided having a central bore 15, the lower end of the bore being internally threaded for engaging the upper end of the oil tubing, while its upper end is conically formed for the reception of an elastic conical packing plug 16, having an aperture 17 to permit the passage therethrough of the pump rods 18. Spider 14 is mounted directly above the body 5, its lower annular end engaging a packing ring 19 disposed on the upper end of the split sleeve. By interposing this packing ring between the spider and collar all gas flowing from the well will be directed through the gas outlets in the collar. Bore 15 of the spider is provided intermediate its end with laterally extending diametrically disposed oil flow pipes 20, to provide for the discharge of the oil as it is pumped from the well, the pipes leading to storage tanks not shown.

To expand the packing plug 16 in fluid tight engagement with the upper conical end of bore 15, a gland follower 21 cylindrical in form is employed, provided with a central bore 22 for the free passage of the pump rods, its lower end engaging the upper end of the packing plug to expand the same when pressure is applied thereto. Formed integral with the follower are a pair of diametrically disposed laterally extending arms 23, their outer ends being forked for the reception of the anchoring bolts 24, whose lower ends are enlarged and provided with openings 25 of a size sufficient to loosely engage the gas flow pipes when the casing head is assembled. The upper ends of these bolts are of reduced diameter as at 26, the ends of both portions being threaded for the reception of adjusting nuts 27, 28, nuts 27 bearing against the upper faces of the laterally extending arms 29 formed integral with the spider 14, each of their outer ends being forked for the passage therethrough of the anchoring bolts, while nuts 28 bear against the upper faces of the arms 23.

That portion of the bore 15 directly below the conical upper end is threaded as at 30 for the reception of a screw plug (not

shown) to lift the spider and the connected oil tubes when desired.

The casing head can be used with flowing wells by simply removing the expansible 5 plug and applying a valve to the upper threaded end of the spider.

By simply manipulating the nuts 27 a gas tight joint will be formed between the collar and the spider, and the gland follower 10 21 may be similarly forced downwardly by means of the nuts 28 to expand the plug into fluid tight engagement with its seat.

From the above description it will be apparent that I have provided a simple casing 15 head that effectively combines several important elements in a single unitary structure that were formerly employed in a number of structures connected together by pipe connections.

20 29 What I claim is:

1. A casing head for oil wells comprising a body member having an internal seat adjacent its upper end adapted to be detachably secured to the upper end of a well casing and 25 having gas outlet pipes leading therefrom, a sleeve having a conical bore for the reception of tubing slips mounted on the seat of the body member, an expansible packing member mounted on the upper end of the sleeve, 30 a spider member having a bore therethrough and fluid outlets leading therefrom disposed on said packing member, a packing member disposed in the upper end of said spider bore having an aperture for the passage of pump 35 rods therethrough, the lower end of said bore being threaded for the reception of the upper

end of a string of oil tubing, a gland follower bearing against said packing member to compress the same, and means to secure the spider to the body and to simultaneously expand the packing members. 40

2. A casing head for oil wells comprising a lower bored member and an upper bored member, the longitudinal axis of the bores of said members being in alignment, each of 45 said bores having fluid outlets leading therefrom, a packing means between said members, a rod packing gland in the upper end of the bore of the upper member, means to secure the two members together in gas 50 tight engagement and to compress the rod packing gland, said casing head adapted to be detachably secured to the upper end of a well casing, and means on the upper member for securing a string of oil tubing thereto in 55 alignment with its bore.

3. A casing head for oil wells comprising bored upper and lower members having a packing therebetween and means to detachably secure the same together, said casing 60 head adapted to be secured to the upper end of a well casing, said members each having fluid outlets leading from their bores, a rod packing disposed in the upper end of the bore of the upper member and means to compress the same, and a slip supporting sleeve 65 detachably mounted in the bore of the lower member.

In witness that I claim the foregoing I have hereunto subscribed my name this 2nd 70 day of October, 1925.

WILSON B. WIGLE.
